UNITED STATES PATENT OFFICE

KARL F. STARZ, OF ELIZABETH, NEW JERSEY

PROPELLER

Application filed April 14, 1930. Serial No. 444,307.

This invention relates to improvements in propellers, the general object of the invention being to provide means whereby the pitch of the blades of the propeller can be varied from the cockpit of a craft so as to regulate the speed of the craft through the set of the blades, which will permit the craft to be operated with the minimum amount of fuel.

10 This invention also consists in certain other features of construction and in the combination and arrangement of the several parts, to be hereinafter fully described, illustrated in the accompanying drawings and 15 specifically pointed out in the appended claims.

In describing the invention in detail, reference will be had to the accompanying drawings wherein like characters denote like 20 or corresponding parts throughout the several views, and in which:—

Figure 1 is an end view showing the central part of a propeller constructed in accordance with this invention.

25 Figure 2 is a section on line 2—2 of Figure 1.

Figure 3 is a section on line 3—3 of Figure 2.

Figure 4 is a section on line 4—4 of Figure 30 1, showing the parts set with the blades in a neutral position.

Figure 5 is a section on line 5—5 of Figure 1, with the parts in the same position they occupy in Figure 4.

35 Figure 6 is a view similar to Figure 4 and Figure 7 is a view similar to Figure 5, but showing the parts in different positions.

Figure 8 is a view similar to Figure 4 and Figure 9 is a view similar to Figure 5, but 40 showing the parts in other positions.

In these drawings, the numeral 1 indicates the propeller shaft and 2 indicates a hub mounted on the shaft and formed with a sleeve 3 which extends over a part of the 45 shaft, the hub and sleeve and the shaft being tapered, as shown.

The hub is formed with a number of hollow spokes 4 over which the stems 5 of the blades fit, so that the stems are rotatably arranged 50 on the hub. A flange 6 is rotatably arranged

on each end of the hub, each flange being formed with the extensions 7 which have holes 8 adjacent their ends for receiving the trunnions 9 on a collar 10 formed on each stem 5. Each stem 5 is clamped to a spoke by a 55 split collar 11, the bent ends of which are connected together by a bolt 12. Thus each stem is firmly connected to a spoke and the two trunnions of each stem enter the holes 8 of a pair of extensions 7 of the flanges 6. 60 A number of levers 12^a is pivoted to the hub adjacent their outer ends, as shown at 13, each lever being arranged between a pair of the spokes and each lever passes through an opening 14 formed in each flange 6. The inner ends of these levers carry the rolls 15 which engage the cam grooves 16 in a collar 17 mounted on the sleeve 3 and having a groove 18 therein for receiving a shifting fork (not shown), this fork being connected to a 70 lever or the like in the cockpit. Thus it will be seen that by shifting the collar 17, the cam grooves 16 will, through the rollers 15, shift the levers 12^a, and as these levers pass through holes in the flanges 6, this shifting 75 movement of the levers will move one flange in one direction and the other in the opposite direction so that the blades will be partly rotated and thus their pitch will be changed.

Figures 4 and 5 show the parts in a central 80 position, Figures 6 and 7 show the parts shifted in one direction beyond a central position and Figures 8 and 9 show the parts shifted in an opposite direction beyond a central position.

Thus I have provided simple means for adjusting the pitch of the propeller blades so that the speed of the craft can be controlled by regulating the pitch, and this will permit the craft to be driven with the minimum 85 amount of fuel as the internal combustion engine can operate at its most economical rate of speed at all times through a constant load, low pitch at take-off and high pitch in flight.

It is thought from the foregoing description 90 that the advantages and novel features of the invention will be readily apparent.

It is to be understood that changes may be made in the construction and in the combination and arrangement of the several parts, 100

provided that such changes fall within the scope of the appended claims.

What I claim is:—

1. A propeller comprising a shaft, a hub on the shaft, a pair of flanges rotatably arranged on the hub, propeller blades having their stems arranged between the flanges with their ends rotatably arranged on the hub, trunnions on the stems and the flanges having openings therein receiving the trunnions and means for moving the flanges in opposite directions to partly rotate the stems to change the pitch of the blades.

2. A propeller comprising a shaft, a hub on the shaft, a pair of flanges rotatably arranged on the hub, propeller blades having their stems arranged between the flanges with their ends rotatably arranged on the hub, trunnions on the stems and the flanges having openings therein receiving the trunnions, means for moving the flanges in opposite directions to partly rotate the stems to change the pitch of the blades, such means comprising a collar slidably arranged on a part of the hub and having cam grooves therein, levers pivoted to the hub and passing through openings in the flanges and rollers on the levers engaging the cam grooves.

In testimony whereof I affix my signature.
